(57) CLAIM

The ornamental design for a hinge, as shown and described.

DESCRIPTION

FIG. 1 is a top front perspective view of the invention, shown in a closed position.

FIG. 2 is a top plan view of FIG. 1.

FIG. 3 is a front elevation view of FIG. 1.

FIG. 4 is a left side elevation view of FIG. 1.

FIG. 5 is a right side elevation view of FIG. 1.

FIG. 6 rear elevation view of FIG. 1.

FIG. 7 is a bottom plan view of FIG. 1.

FIG. 8 is a top front perspective view of the invention, shown in an open position.

FIG. 9 is a top plan view of FIG. 8.

FIG. 10 is a front elevation view of FIG. 8.

FIG. 11 is a left side elevation view of FIG. 8.

FIG. 12 is a right side elevation view of FIG. 8.

FIG. 13 rear elevation view of FIG. 8; and,

FIG. 14 is a bottom plan view of FIG. 8.

The broken lines are included for illustrative purposes only and form no part of the claim.
